United States Patent

Des. 235,364
Patented June 10, 1975

235,364

PLANT FEEDER

Arthur L. Fassauer, Canyon, Tex., assignor to
Fassauer Industries, Inc., Canyon, Tex.

Filed May 7, 1973, Ser. No. 357,874

Term of patent 14 years

Int. Cl. D11—02

U.S. Cl. D35—3 A

Figure 1

Figure 2

Figure 3

FIG. 1 is a front perspective view of a plant feeder showing my new design;

FIG. 2 is a front elevational view; and

FIG. 3 is a top plan view thereof.

I claim:

The ornamental design for a plant feeder, as shown and described.
